CLAIM

I claim, the ornamental design for an LED luminaire, as shown and described.

DESCRIPTION

FIG. 1 is a perspective view of an LED luminaire showing our new design.

FIG. 2 is a right side view of the LED luminaire shown in FIG. 1.

FIG. 3 is a left side view of the LED luminaire shown in FIG. 1.

FIG. 4 is a front view of the LED luminaire shown in FIG. 1.

FIG. 5 is a back view of the LED luminaire shown in FIG. 1.

FIG. 6 is a top view of the LED luminaire shown in FIG. 1; and,

FIG. 7 is a bottom view of the LED luminaire shown in FIG. 1.

The broken lines in the drawings illustrate portions of the LED luminaire which form no part of the claimed design.
